Inventor:

UNITED STATES PATENT OFFICE.

FREDERICK A. MANAU, OF CHICAGO, ILLINOIS, ASSIGNEE TO BENJAMIN ELECTRIC MANUFACTURING COMPANY, A CORPORATION OF ILLINOIS.

SWITCH.

1,399,781.

Specification of Letters Patent. Patented Dec. 13, 1921.

Application filed June 19, 1917. Serial No. 175,502.

To all whom it may concern:

Be it known that I, FREDERICK A. MANAU, a citizen of the United States, residing at Chicago, in the county of Cook and State 5 of Illinois, have invented new and useful Improvements in Switches, of which the following is a full, clear, concise, and exact description, reference being had to the accompanying drawing, forming a part of this 10 specification.

My invention relates to switches.

Among the objects of my invention is to provide an improved canopy-switch which will be compact in construction, durable and 15 efficient in use, and cheap to manufacture.

Further objects will appear from the detailed description to follow and from the appended claims.

In the drawings, in which one embodiment of my invention is shown—

Figure 1 is a vertical axial section showing a canopy-switch embodying my invention;

Fig. 2 is a horizontal section on the line 2—2 of Fig. 1;

Fig. 3 is a horizontal section on the line 3—3 of Fig. 1;

Fig. 4 is a vertical section on the line 4—4 of Fig. 2;

Fig. 5 is a vertical section substantially on the line 5—5 of Fig. 2;

Fig. 6 is a vertical section on the line 6—6 of Fig. 2;

Fig. 7 is a vertical section on the line 7—7 of Fig. 2; and

Fig. 8 is a vertical section on the line 8—8 of Fig. 3.

Referring now to the drawings in detail, my invention is shown in connection with an 40 outlet-box 10 and a canopy 11 which may be of any usual or suitable construction. The switch mechanism 12 is held and supported in a two-part cage 13, which is supported from the outlet-box 10 by a connection including an insulating joint 14. A tubular stem 15 is threaded into the lower portion 16 of the two-part cage 13, forming a passage for the conductors 17, and also forming a mechanical support for any suitable 45 translating device, such as a lighting unit. A pull-chain 18 for operating the switch leads from the switch-mechanism 12, the canopy 11 being provided with an opening 19 through which this pull member passes,

and being also provided with an opening 20 through which the stem 15 passes. The outlet-box 10 is provided with a suitable opening 21 through which the conductors 17 enter and from which they lead to the switch-device 12.

The upper portion 22 of the two-part cage is threaded on to a nipple 23, which extends downwardly from the insulating joint 14 and which is supported thereby.

The canopy 11 may be supported in position by means of a set-screw 24 threaded through a reinforcing and finishing ring 25, the point of which screw engages the stem 15.

The switch-mechanism 12 comprises a three-part insulating base 26, a rotatable step-by-step switch member 27, and a pair of spring contact members 28 and 29, which co-operate with the rotatable switch member 27 to make and break the circuit. The member 27 is rotatably mounted on a shaft 30 of conducting material and is operated by means of a switch-arm or lever 31, to which the pull-chain 18 is connected, and the ratchet-mechanism 32 interposed between the arm 31 and the rotatable member 27. For returning the arm 31 after it has been operated by means of the pull-chain 18, a spring 33 is provided surrounding the shaft 30.

The rotatable member 27 comprises an insulating support 34 in the shape of a ratchet wheel and a contact and conductor member 35 comprising contact portions 36 lying on top of the teeth of the ratchet-shaped support 34 for engagement with the spring contact 29, and a conducting portion 37 extending across the face of the ratchet-shaped support 34 and electrically connecting the portions 36 with each other and with the shaft 30. The switch is provided with two binding-terminals 38 and 39, respectively, the binding-terminal 38 being electrically connected with the spring contact members 28 and 29, and the binding-terminal 39 being electrically connected with the shaft 30. The electrical connection between the binding-terminal 38 and the spring contact member 28 is effected by means of the screw 40, which holds the member in place on the base 26 and is threaded into the binding-plate 41 of the binding-terminal 38.

The binding-terminal 39 is electrically

connected with the shaft 30 by means of the screw 42 threaded into the binding-plate 43 of the binding-terminal 39, and the strap 44, one end of which is wrapped around the shaft 30 and the other end of which is held beneath the head of the screw 42 (Fig. 6).

In wiring the device, one of the conductors 17 extends unbroken through the three-part base 26, as shown in Fig. 8. The other conductor 17 is broken and one end is fastened to the binding-screw 45 of the binding-terminal 38, and the other end is fastened to the binding-screw 46 of the binding-terminal 39.

15 The three parts 47, 48 and 49 of the insulating base 26 are provided with registering openings for the passage of the conductors 17. The parts 48 and 49 are provided with registering recesses 50 and 51 to accommodate the rotatable switch member 27 and associated parts.

20 The circuit when the switch is closed is from the binding-terminal 38, through the screw 40, contact members 28 and 29, contact portion 36, conductor portion 35, shaft 30, strap 44 and screw 42 to the binding-terminal 39.

25 The step-by-step rotation of the rotatable member 27 alternately makes and breaks the circuit between the contact member 29 and the shaft 30, and, hence, between the binding-terminals 38 and 39. The end of the shaft opposite that to which the strap 44 is secured is held in place by means of a strap 35 52, one end of which is wrapped around the shaft 30 and the other end of which is held beneath the head of a screw 53, which extends through openings in the insulating portions 48 and 49 and is threaded into a 40 nut 54 (Fig. 7).

30 The two parts—16 and 22—of the cage 18 are secured together by means of screws 55 extending through ears 56 and 57 on the two parts of the cage.

35 45 What I claim as new and desire to secure by Letters Patent of the United States is:

1. In a canopy-switch device, a threaded support, a two-part skeleton cage one part 50 of which is secured to said support, a switch held in place by said cage, a hollow stem secured to the other part of the cage for supporting an electrical translating device, a canopy having an opening through which said stem extends, and a pull member for 55 operating said switch extending from said canopy.

2. A device comprising an insulating base including two insulating members having 60 registering openings and recesses, two binding-terminals supported by said base, a pull-switch mechanism mounted in said recesses for making and breaking connection between said terminals, two conductors, one connected to each terminal, an insulated 65 conductor extending through said openings,

a cage for holding and supporting said base, a hollow stem secured to said cage with a passage registering with the openings in said insulating members, a pull member for operating said switch, and a canopy for 70 housing said cage and said base having passages through which said stem and pull member extend.

3. A device comprising an insulating base, including two insulating members having 75 registering openings and recesses, two binding-terminals supported by said base, a switch-mechanism mounted in said recesses for making and breaking connection between said terminals, two conductors one 80 connected to each terminal, an insulated conductor extending through said openings, a cage for holding and supporting said base, a hollow stem secured to said cage with passage registering with the openings in said 85 insulating members, and a canopy for housing said cage and base having an opening through which said stem extends.

4. A device comprising an insulating base including two insulating members having 90 registering openings and recesses, two binding-terminals supported by said base, a switch-mechanism mounted in said recesses for making and breaking connection between said terminals, two conductors one 95 connected to each terminal, an insulated conductor extending through said openings, a cage for holding and supporting said base, and a hollow stem secured to said cage with its passage registering with the openings in 100 said insulating members.

5. In a canopy-switch device, an electrical outlet, a support depending therefrom, a canopy covering said outlet, a two-part cage secured to said support, a pull-switch mechanism provided with a pull member in said cage, a tubular stem extending downward from said cage, said canopy having passages through which said stem and said pull member extend, said cage comprising two 110 portions separable along a substantially horizontal plane, and means for securing said portions together.

6. In a canopy-switch device, an electrical outlet, a support depending therefrom, a 115 canopy covering said outlet, a two-part cage secured to said support, a pull-switch mechanism provided with a pull member in said cage, a tubular stem extending downward from said cage, said canopy having passages 120 through which said stem and said pull member extend, said cage comprising two portions separable along a substantially horizontal plane and having substantially vertical registering openings therein, and means 125 for securing said portions together extending through said openings.

7. In a switch device, a spider, means for securing said spider adjacent an outlet, a second spider, means for securing the legs 130

of said spiders together to form a cage, and a pull switch mechanism inclosed in said cage.

8. In a canopy switch, a spider, means for securing the central portion of said spider to a support, a second spider, means for securing the legs of said spiders together to form a cage, a hollow stem secured to the central portion of said second spider, a pull switch located in said cage, a canopy having an opening through which said stem extends, and a pull member for operating said switch extending from said canopy.

9. In a canopy switch device, a threaded support, a spider having its central portion threaded to engage said support, a second spider, means for securing the legs of said spiders together to form a cage, a hollow stem secured to said second spider for supporting an electrical translating device, a canopy having an opening through which said stem extends, a switch held in place in said cage, and a pull member for operating said switch extending from said canopy.

25 10. In a switch device, a spider, means for supporting said spider adjacent an outlet, a second spider, means for securing the legs of said spiders together to form a cage, a supporting stem secured to said second spider, and a pull switch held in place in said cage, said pull switch comprising a substantially cylindrical insulating support having a vertical axis and switch mechanism supported thereby.

35 11. In a canopy switch device, a spider, means for supporting said spider adjacent an outlet, a second spider, means for securing the legs of said spiders together to form a cage, a supporting stem secured to said second spider, and a pull switch held in place in said cage, said pull switch comprising a substantially cylindrical insulating support having a vertical axis and switch mechanism supported thereby, the legs of said second spider extending substantially the length of said insulating support.

12. A canopy switch device comprising an insulating base having two parts separable along a substantially horizontal plane, a switch mechanism inclosed between said parts, a cage for inclosing and supporting said base comprising two parts separable along a substantially horizontal plane, a support above said cage to which the upper part of said cage is secured, a tubular stem secured to the lower part of said cage and extending downwardly therefrom, a pull switch member for operating said switch, and a canopy for housing said cage and switch mechanism having passage means through which said stem and pull member extend.

65 13. A canopy switch device comprising an insulating base having two parts separable

along a substantially horizontal plane, a switch mechanism inclosed between said parts, a cage for inclosing and supporting said insulating base comprising two portions separable along a substantially horizontal plane, the lower portion of said cage constituting a receiver for said insulating base for holding the parts of the base in their proper positions, a support above said cage to which the upper portion of the cage is secured, a tubular stem secured to the lower portion of the cage, a pull member for operating the switch, and a canopy for housing said cage and insulating base and having passage means through which said pull member and tubular stem extend.

14. A canopy switch device comprising an insulating base having two portions separable along a substantially horizontal plane, a switch mechanism inclosed between said parts, a cage for inclosing and supporting said base comprising two parts separable along a substantially horizontal plane, a support above said cage to which the upper part of said cage is secured, a tubular stem secured to the lower part of said cage and extending downwardly therefrom, a pull switch member for operating said switch, and a canopy for housing said cage and switch mechanism, having passage means through which said stem and pull member extend, said base having an opening there-through for the passage of a conductor from above said insulating base to said tubular stem.

15. A canopy switch device comprising an insulating base having two parts separable along a substantially horizontal plane, a switch mechanism inclosed between said parts, a cage for inclosing and supporting said base comprising two parts separable along a substantially horizontal plane, a support above said cage to which the upper part of said cage is secured, a tubular stem secured to the lower part of said cage and extending downwardly therefrom, a pull switch member for operating said switch, and a canopy for housing said cage and switch mechanism, having passage means through which said stem and pull member extend, said base having a binding-terminal for a conductor leading from above said insulating base and having another binding-terminal for a conductor leading to said tubular stem.

16. In an electric lighting fixture, an electric switch containing member, arranged for connection with supporting members above and below it, and comprising two separable companion switch clasping members, a pull switch separate from said switch containing member and removably held therin and means for securing said switch clasping members together around said switch.

17. In an electric lighting switch, a pull switch containing member, arranged for connection with lamp supporting members above and below it, and a pull switch separate from said container and removably secured therein.
18. In an electric lighting fixture, a pull

In witness whereof, I have hereunto subscribed my name.

FREDERICK A. MANAU.
